UNITED STATES PATENT OFFICE.

JOHN A. HULT, OF CLEVELAND, OHIO, ASSIGNOR TO THE AMERICAN MULTIGRAPH COMPANY, OF CLEVELAND, OHIO, A CORPORATION OF OHIO.

PRINTING MECHANISM.

Application filed July 8, 1927. Serial No. 204,175.

This invention is concerned with a supplemental printing mechanism adapted to be attached to a multigraph to print the signature on a letter printed on the multigraph. 5 The mechanism of the present invention is an improvement on that of Patent No. 1,117, 751 granted November 17th, 1914 to The American Multigraph Company as assignee of William R. Allen. The primary feature 10 of the present invention comprises signature printing means adapted to be readily located in any desired position transversely of the sheet. Accessibility of the signature roller for convenient mounting of the signature 15 plate, is also a feature; also a laterally adjustable paper feeding mechanism; also various details of construction contributing to the efficiency of the mechanism. The invention illustrated in the accompanying 20 drawings will hereinafter be more fully described.

In the drawing, Fig. 1 is a sectional side elevation of a multigraph with my signature attachment mounted thereon; Fig. 2 is a substantial vertical section (partly broken out) 25 on a plane indicated by the line 2—2 on Fig. 1; Fig. 3 is a cross-section through the multigraph and signature attachment, looking in the opposite direction to Fig. 1 and indicated by the line 3—3 on Fig. 2; Figs. 4 and 30 5 are cross-sections on their respective numbered lines on Fig. 2, looking toward the right of that figure; Fig. 6 is a sectional plan of the inking mechanism for the signature 35 roller, on a plane indicated by the line 6—6 on Fig. 1; Fig. 7 is a detail illustrating the 40 slidable mounting of one of the end members of the signature roller; Fig. 8 is a perspective of the sliding key shown in Fig. 7; Fig. 9 is an approximately horizontal cross- 45 section through the main cam and its roller, as indicated by the line 9—9 on Fig. 1; Fig. 10 is a detail illustrating the sliding connection of the mechanism for lowering the 50 signature roller, being a substantially vertical section on the line 10—10 on Fig. 4; Fig. 11 is a perspective of one of the members of the 55 variable coupling for driving the signature roller; Fig. 12 is a rear elevation of the signature attachment; Fig. 13 is a detail in side elevation of the double-acting spring mechanism for positioning the cam arm.

In Figs. 1 and 3 I have shown the multigraph frame comprising vertical end plates 55 10 and 11 carried by a base portion 12.

Mounted in these end plates is a main shaft 14, about which is suitably mounted a segment 15 carrying a printing member 16. A suitable under-rolling platen 17 coacts with such arcuate printing member. 18 designates a ribbon on the drum extending about the printing surface. These parts are usual in a multigraph.

Secured to the rear side of the base frame 12 of the multigraph, is a base frame 20 of 65 the signature attachment having end plates 21 and 22. Suitably carried by these end plates is the shaft 30 on which is mounted eccentrically a sleeve 32, journalled on which is a cylindrical sleeve 34 which I call the signature roller. This roller carries an arcuate signature printing plate 35 which is adapted to coact with a rotary platen. The signature plate is inked by engagement with a transfer roller 51, which coacts with an absorbent supply roller 52, and thus a sheet 70 passed rearwardly from the multigraph between the supplemental printing couple described, may have the signature printed 75 thereon.

The eccentric 32 is normally in the position shown in Fig. 2, maintaining the signature roller out of contact with the platen roller 40 but in contact with the ink transfer roller 51. Suitable gearing hereinafter described 80 constantly drives the shaft 30 and the shaft 50 carrying the transfer roller, and thus maintains the signature plate inked. At the proper time the eccentric sleeve 32 is turned to lower the signature roller 34 into position 85 to coact with the platen roller 40. Mechanism for effecting this will now be described.

In Figs. 1, 4, 5, 9 and 12, appears a grooved cam 60 mounted on a stud 61 carried by the frame plate 22. This cam member has external gear teeth 63 by which it is geared with the shafts 30 and 50 and the multigraph machine, as hereinafter explained. Pivoted to the frame plate 22 is an arm 70 which may swing either way from its normal position 90 and carries a roller 71 which may occupy the groove 65 of the cam or engage the exterior of the cam. This arm is connected by a link 73 to a rock arm 74 rigid on a rock shaft 75, journalled in the frame members 21 and 22. Splined on this rock shaft is a double armed 95 rock lever 77, shown in Fig. 12 and in dotted line in Fig. 4. Loosely mounted on the rock shaft is a lever 80, which has a pair of arcuate slots 81 and 82 concentric with the rock 100 105 110

shaft. Suitable screws 83 and 84 pass through these slots and clamp the arm 80 adjustably to the lever 77. A link 85 connects the lower end of the lever 80 with an arm 87 on the end of the eccentric sleeve 32.

It results from the above construction that as the cam 60 is rotated, the shaft 75 is rocked, first in one direction and then in the other, and this rocking turns down the eccentric sleeve 32 to bring the signature plate to active position for printing, and thereafter restores it. The adjustment, by reason of the angularly fixed rock arm 77 and the independently rotatable arm 80 with the slots and the clamping screws, enables an initial positioning of the eccentric to compensate for varying thicknesses of the signature plate 35 and also to vary the intensity of inking, or, as it is called, "depth of impression."

The gearing between the multigraph drum and the signature attachment may be set, as explained in the Allen patent mentioned, and as hereinafter described, to cause the cam 60 to turn down the signature plate at any desired time with reference to the drum, and this locates the signature at the proper vertical position on the page to come beneath the matter printed. It is desirable however, that the signature be adjustable laterally on the page, and the provisions for that purpose constitute an important part of this invention.

The signature roller, the ink transfer roller and the felt supply roller, and certain paper feed rollers are all shiftable along their respective shafts, while the platen roller 40 is made long enough so that a portion of it will always be opposite the signature plate, irrespective of the position of the latter. The eccentric operating link 85 and its driving levers 77 and 80 are also shiftable along the shaft 75 simultaneously with the signature roller. Thus the arm 77 is splined to the rock shaft 75, and the eccentric sleeve 32 is indirectly splined to the shaft 30 so that the mechanism for turning the eccentric and the signature roller are shiftable as a unit.

To lock the turning mechanism in position without moving its shaft, I provide intermediate members as follows, namely: The set screw 90 (Fig. 10) on the arm 77 bears against a key 91 which occupies the keyway 92 in the shaft 75. This key has outwardly projecting end portions, so that it must shift with the arm 77. It furnishes at once the desired splined connection between the arm and the shaft and also a distribution block between the set screw and the bottom of the keyway.

The set screw 94 (Figs. 2 and 6) for locking the transfer roller 51 to the shaft 50, is located in a collar 95 surrounding a slotted extension of the hub sleeve 96 of that roller and the set screw thus binds this hub exten-

sion onto the shaft 50. The felt roller 52 is loose on its shaft 54 but it carries a disc 55, the edge of which occupies an annular groove 97 in the collar 95 so that these two inking rollers cannot shift independently of each other. The arm 87 attached to the eccentric sleeve 32 spreads out into a sector, as shown in Fig. 4, which overlaps the end of the hub 96 of the roller 51 and thus furnishes a gauge for bringing that roller into proper relation with the set eccentric.

As the adjustment between the eccentric sleeve 32 and the rock shaft 75, heretofore described, will change the relation of the signature roller 34 to the axis of the shaft 30, it is desirable to provide a shiftable coupling between them, and at the same time, since the signature device shifts longitudinally on the shaft it is desirable that such coupling be of such form that it will not separate during shifting. To effect this, I provide a modified form of Oldham coupling, illustrated in Figs. 2, 7, 11 and 12. That is to say, in the right hand end of the signature roller 34 is a diametric pair of undercut or dovetailed notches; adjacent this end is a ring 100 having a pair of flaring or dovetailed ribs 101 occupying such notches. On the opposite side of this ring are dovetailed ribs 102 located 90° from the ribs 101. These ribs occupy diametric undercut grooves in a collar 105, splined to the shaft 30.

This splining of the collar 105 on the shaft 30 is effected in a manner similar to that described for the arm 77. That is to say there is a keyway 106 in the shaft and this is occupied by a key 107 (Figs. 7 and 8) which extends through the collar and has end projections 108 overlapping the collar, the collar being recessed on the left side to receive such projection. The set screw 109 forces this key against the shaft.

It must be understood from the description given, that the printing roller with its eccentric mounting, and its movably connected driving collar 105, are all shiftable as a unit on the shaft 30 coincident with that of the eccentric rocking mechanism on the shaft 75. If this shifting is toward the right in Fig. 2, it may carry the inking rollers with it, by reason of the overlapping sector arm 87; if it is toward the left, the signature roller and operating parts may be carried away from the inking rollers, and thereafter the inking roller brought up to position until the hub 96 of the roller 51 abuts the arm 87.

The provision just described for separating the inking rollers from the signature roller, enables the inking rollers to be shoved to the right independently of the signature roller to entirely clear the same, so that the signature plate may be easily installed on the roller 34. This installation may be readily accomplished by suitable screws passing into

the signature roller and overlapping the signature plate or by clips, indicated at 109 (Fig. 2) on the signature roller.

I utilize the long platen roller 40 as one member of a rotary delivery system for the signature attachment. The other members comprise rollers 110 and 111 splined on the shaft 30 and shiftable longitudinally, as desired. The roller 111 is preferably hollowed, 10 on its left side or made cup-shape, as shown at 112, to enable it to pass over the driving collar 105 of the shiftable coupling, if desired.

The platen roller 40 is preferably eccentrically mounted to obtain adjustment for different thicknesses of paper. To this end, the elastic surface surrounds a shaft 120 (Fig. 2) which is journaled on eccentric studs 121 and 122 projecting from pins 123 and 124 20 rotatively carried in the respective frame plates 21 and 22, and clamped by suitable set screws 125 and 126. This adjustment for both the printing and feeding takes care of the different thicknesses of paper. The adjustment 25 heretofore described, in the eccentric operating mechanism, allows for a different thickness of signature plate 35 and different depth of impression. Lateral adjustment of the signature printing members enables the 30 positioning of this signature as desired, laterally on the sheet, while the adjustment of the feed rollers provides for different widths of sheet.

As heretofore explained, the adjustment of the signature for different positions up and 35 down the sheet, is provided by the gearing connecting it with the multigraph, which will now be described. As shown in Fig. 3, the multigraph drum is provided with a gear 130. This gear, besides meshing with a gear 131 40 on the multigraph platen and the gear 132 on the multigraph ejector mechanism, meshes with a gear 135 connecting with the signature attachment. This gear 135, as explained in the Allen patent referred to, is shiftable 45 into and out of mesh with the multigraph gear, thus entirely freeing the signature attachment, whereby the latter may be set in any position with reference to the matter on the drum. The gear 135, when in mesh with 50 the multigraph gear 130, also meshes with a gear 140 rigid on the shaft 30. This gear 140 meshes also with a gear 144 which meshes with a gear 145 on the shaft 54 of the inking supply roller, and this gear 145 meshes also 55 with a gear 145 on the shaft 50 of the transfer roller. On the shaft 30 is a pinion 147 (Fig. 2) meshing with the spur gear 63 formed on the cam 60.

The Allen patent referred to, provides the 60 cam roller 71 in such manner that it may be entirely withdrawn from the cam 60 to disconnect the signature operation without changing the gear connection to the multigraph. A similar arrangement is shown in 65 Fig. 9, wherein this roller 71 is mounted on

the end of a rod 170° which is slidably mounted in a housing 171 carried by a rock arm 70 and pressed toward the cam by a spring 172. A head 173 on the rod furnishes means for moving it longitudinally, and if drawn out 70 into a position to clear the cam, it will be locked in that position by a spring 174, engaging a notch in the rod, this spring being strong enough to hold the rod with the spring 172 compressed. A slight pressure however, 75 on the end of the rod, will release it from the spring and restore it to position.

As the rock arm moves in each direction from its normal position of rest,—the roller, 80 part of the time, being in the cam groove 60, and, part of the time, about the periphery 64 of the cam,—the Allen patent referred to provides a pair of compression springs acting alternately on a rod connected to the arm 70. However, it has been found difficult to maintain these springs with proper force relative 85 to each other and I have accordingly provided the construction shown in Figs. 1 and 13, which I will now describe.

The arm 70 which carries the cam roller 71 90 is rigid on a short rock shaft 80, while loose on the rock shaft are a pair of arms 181, which are connected by a tension spring 183 and thus normally drawn against an intermediate stop rod 184, carried by the frame. The rock 95 shaft 180 has an upward lug 185 occupying an arcuate notch 186 in the arm 181; the lug being normally in the right hand end of the slot (Fig. 13). Similarly the rock shaft has a downward lug 187 at the right hand end of 100 an arcuate slot 188 in the arm 182. From this construction, it follows that if the arm 70 is swung to the right (Fig. 13) the arm 181 is lifted and the spring 183 stretched, while the arm 182 bearing against the underside of 105 the rod 184 forms an anchor. If the arm 70 is swung to the left in this figure, the arm 182 is swung downwardly, stretching the spring 183 while the arm 181, engaging the top of the rod 184, acts as an anchor. This mechanism 110 has been found to be very satisfactory in holding the arm 70 normally in a definite intermediate position while allowing it to move in either direction therefrom, as the cam groove and the periphery between the ends of the 115 groove act successively on the roller.

I claim:

1. The combination, with a multigraph, of a signature attachment comprising a signature carrying drum and a platen, means for rotating the drum, said drum being so mounted that it may be shifted longitudinally into various positions and still be operable, the platen being long enough to accommodate 120 all such positions without shifting.

2. The combination of a multigraph, a signature attachment comprising a platen, a drum carrying a signature plate, means for rotating the drum and platen and for causing 125 them to approach, characterized in that the 130

signature drum is shiftable longitudinally without disconnecting its operating mechanism, while the platen is long enough to accommodate without shifting all such positions of the drum.

3. The combination with a platen, of a roller adapted to carry a printing member, eccentric on which the roller is mounted, periodically acting mechanism for turning 10 said eccentric to cause the roller to approach the platen or recede from it, the eccentric and its operating mechanism being shiftable longitudinally as a unit.

4. The combination of a platen, a shaft 15 parallel therewith, an eccentric sleeve longitudinally shiftable on said shaft, a printing roller mounted on the sleeve, a second shaft parallel with the shaft first mentioned, mechanism mounted on the second shaft and longitudinally shiftable thereon for actuating 20 such eccentric sleeve.

5. The combination of a platen, an eccentric, a printing cylinder surrounding the eccentric, a rock shaft, means for rocking said 25 shaft, an arm on said shaft, a link connecting said arm with an arm on the eccentric, said arms, link and eccentric being shiftable longitudinally as a unit.

6. The combination, with a platen, of a 30 printing roller rotatably mounted and shiftable longitudinally, an ink transfer roller coacting with the printing roller, an ink supply roller coacting with the transfer roller, said supply roller and transfer roller being 35 coupled together for unitary shifting longitudinally thereof, and means for preventing the transfer roller shifting beyond the printing roller in one direction but leaving it free to move in the opposite direction.

40 7. In a printing device, the combination of a platen, a shaft parallel therewith, an eccentric sleeve on the shaft, mechanism for turning said eccentric sleeve, a sleeve surrounding the eccentric sleeve, a signature 45 plate removably attached to said surrounding sleeve, an ink supply roller and an ink transfer roller engaging each other and shiftable as a unit, said transfer roller being adapted to coat with the signature plate or be shifted 50 out of registration therewith to allow the installation of such signature printing plate.

8. In a printing device the combination 55 of a platen, a shaft parallel therewith, an eccentric sleeve on the shaft, a printing roller surrounding said shaft and shiftable thereon, mechanism for turning said eccentric sleeve mounted on another shaft and also shiftable longitudinally, a printing sleeve surrounding the eccentric sleeve, an ink supply roller and an ink transfer roller engaging 60 each other and shiftable as a unit, said transfer roller being adapted to coat with the printing sleeve or be shifted out of registration therewith.

65 9. In a printing machine, the combination

of a shaft, an eccentric sleeve slidably mounted thereon, a printing sleeve surrounding the eccentric sleeve and a shiftable coupling connecting the shaft with the printing sleeve, said coupling being movably anchored to the 70 printing sleeve whereby the coupling and sleeve may be shifted as a unit.

10. In a printing machine, the combination of a shaft, an eccentric sleeve slidably mounted thereon, a printing sleeve surrounding 75 the eccentric sleeve, a collar slidable on the shaft, and a shiftable coupling connecting the collar with the printing sleeve, said coupling being movably anchored to the printing sleeve and to the collar whereby the coupling and sleeve may be shifted as a unit. 80

11. In a printing machine, the combination of an axially shiftable roller, a shiftable driving member therefor, and a coupling between them comprising a ring having on one 85 side a radial rib slidably engaging the roller and on the other side a radial rib at right angles of the first rib slidably engaging said member, each of said ribs flaring to have a dovetailed engagement with its coacting 90 member.

12. In a printing machine, the combination of a shaft, a printing roller mounted thereon and shiftable longitudinally, a comparatively long non-shiftable roller platen with which 95 the printing roller in various positions may coat, and a feeding roller carried by said shaft and engaging the same platen beyond the printing roller.

13. In a printing machine, the combination 100 of a shaft, a printing roller mounted thereon, a platen with which the printing roller may coat, and a feeding roller carried by said shaft, said feeding roller being shiftable on its shaft and being cup-shaped on the 105 side adjacent the printing roller.

14. In a printing machine, the combination of a shaft, a printing roller mounted thereon and shiftable longitudinally, a comparatively long roller platen with which the printing 110 roller, in various positions, may coat, a shiftable coupling connecting said shaft with one end of said printing roller, a feeding roller carried by said shaft beyond said coupling and engaging the same platen beyond the printing roller, said feeding roller being shiftable on its shaft and being cup-shaped on the side adjacent the coupling and thus adapted to surround it. 115

15. In a printing device, the combination 120 of a member eccentrically mounted, mechanism for turning such mounting, including a cam and a lever adapted to swing in either direction from an intermediate position, and mechanism tending to hold the lever in its 125 intermediate position, comprising a rock shaft connected to the lever, a pair of arms on the rock shaft, each having a loose play connection therewith, and spring means acting on both arms. 130

16. In a printing device, the combination and giving them the tendency to engage op- 10
of an eccentrically mounted printing mem- posite sides of the stop, whereby when the
ber, mechanism for turning the eccentric roller arm is moved in either direction the
mounting, including a cam and an arm car- spring is stretched while one of the arms acts
5 ryng a cam roller, said arm being rigid on as an anchorage.
a rock shaft, a pair of arms having loose In testimony whereof, I hereunto affix my
play connection with said rock shaft, said signature.
arms extending onto opposite sides of a stop,
and a tension spring anchored to the two arms

JOHN A. HULT.
